DESIGN FOR A FUR JACKET

Murray Kaufman, New York, N. Y., assignor to
Murray Kaufman, Inc., New York, N. Y., a corporation of New York

Application May 28, 1938, Serial No. 77,448

Term of patent 3½ years

To all whom it may concern:

Be it known that I, Murray Kaufman, a citizen of the United States and resident of New York, in the county of Bronx and State of New York, have invented a new, original, and ornamental Design for a Fur Jacket, of which the following is a specification, reference being had to the accompanying drawing, forming part thereof, in which,

Fig. 1 is a front view of the fur jacket showing my new design; and

Fig. 2 is a rear view of the fur jacket as shown in Fig. 1.

I claim:

The ornamental design for a fur jacket, as shown.

MURRAY KAUFMAN.
